Inventor:
P. Pallissard

UNITED STATES PATENT OFFICE.

P. PALLISSARD, OF AROMA, ILLINOIS.

IMPROVED BABY-WALKER.

Specification forming part of Letters Patent No. 55,529, dated June 12, 1866.

To all whom it may concern:

Be it known that I, P. PALLISSARD, of Aroma, in the county of Kankakee and State of Illinois, have invented a new and improved useful machine named "Baby's Walking-Supporter;" and I do hereby declare that the following is a full, clear, and exact description thereof, which will enable others skilled in the art to make and use the same, reference being had to the following drawings, forming part of this specification, in which—

Figure 1 is a perspective view of this invention. Fig. 2 is a plan view of a circle or hoop provided with eyes. Fig. 3 is a perspective view of a support with its inverted bridge or potence. Fig. 4 is a plan view of the under part of the ring or circle. Fig. 5 is a plan view of a nut, bolt, shoulder, and pivot or caster's turning point.

Similar letters of reference indicate like parts.

The nature of my invention consists in providing the baby with a supporter with the help of which he will walk several months before the time he generally walks, and this without any care on the part of its mother and nurse. The construction of the baby's walking-supporter is such that the baby, always kept straight upon its feet in walking, cannot go near enough to such objects that could injure him, as chairs, stoves, tables, or other obstacles. The circle or hoop of this little machine is built in such a shape that the baby cannot upset it and fall down, that he cannot go through doors of ordinary size, and is by those advantages perfectly safe. The baby can at will go forward and backward and turn in every direction with the utmost facility.

Figure 1 represents a baby's walking-supporter made of solid or hollow iron, cast-iron, brass, wood, or any suitable material.

The hoop A, Fig. 2, the inferior part of the frame, is provided with four eyes, *a a a a*.

B B B B are four supports, provided at one end of each with an eye, *d*, and tapped at the other end, *b*, Fig. 3.

The bolts C C C C, forming by an inferior extension the pivot or turning-point of the caster-wheel, pass at *d*, Fig. 1, through the eyes *a* of the hoop A and the support B at *d*, and pressing those pieces between the shoulder-piece *e* and the nut *f* fasten the same together. (See Fig. 5.)

D D D D are four inverted bridges or potences fastened to the ring E with wood-screws. The end *b* of the support, Fig. 3, is screwed into the central part of the bridge D. The height of the baby's walking-supporter will vary if the support B is screwed or unscrewed.

E is a ring or circle, in which is placed the baby. This ring, Fig. 4, is provided in *gggg* with openings, where the supports B B B B find room when it is necessary to lessen the height of the baby's walking-supporter.

F F F F are four caster-wheels, made of cast-iron, brass, or india-rubber, the pivot or turning-point of which is seen in Fig 5 at *h*.

The baby's walking-supporter can be perfectly used in this simple state, but it can be adorned or embellished to suit taste by any suitable decoration.

I claim as new and desire to secure by Letters Patent—

The arrangement of the hoop A, supported by the caster-wheels F F, and connected with the ring E by the supports B B, having screw-threads cut upon their ends for the ready adjustment of the ring E to the height of the baby, the whole being constructed and operated substantially in the manner and for the purpose set forth.

P. PALLISSARD.
